FIG. 2.

Inventor
WILLIAM T. HANNA,
Murray and Gugelter

Attorney 4

UNITED STATES PATENT OFFICE

WILLIAM T. HANNA, OF CINCINNATI, OHIO

DISTRIBUTOR PLATE

Application filed July 25, 1924, Serial No. 728,274. Renewed July 3, 1929.

This invention relates to fuel distributor plates such as are used in connection with locomotive stokers and the like.

Heretofore it has been found that the fuel distributor plate of a stoker will have the ends which are exposed to the heat in the fire box burned off after continued use.

An object of my invention is to provide a fuel distributor plate having means for protecting the same against the action of the fire box heat and at the same time avoiding impairment of the efficiency of such plate.

Another object is to provide means for the purpose stated which are simple and inexpensive in construction and operation.

Another object is to provide a device of this kind that will require no attention after it has been installed.

These and other objects are attained by the means described herein and disclosed in the accompanying drawings, in which:

Fig. 1 is a cross sectional elevation of a locomotive fire door opening showing in elevation a distributor plate of my invention in an operative position therein.

Fig. 2 is a view on line 2—2 of Fig. 1, looking in the direction of the arrows.

Fig. 3 is a detail of a blast chamber member forming a feature of my invention.

Fig. 4 is a cross sectional view taken in the direction of the arrows on line 4—4 of Fig. 3.

In locomotive structures it has been necessary to dispose the fuel distributor devices substantially within the firing door opening of the locomotive and where such distributors suffered a relatively rapid destruction due to the intense heat in the fire box.

The distributor shown herein comprises a distributor plate 4 mounted at the bottom 5 of the fire door opening 6. A blast chamber member 7 is superposed upon the distributor plate and is instrumental in sorting and distributing the fuel which is disposed thereon by mechanism (not shown). Large pieces of fuel will ride upon the top of the tubular nozzles 8, drop upon the plate 4 and be projected therefrom through the agency of relatively strong blasts of steam issuing from the ends of the nozzles 8. The finer particles of fuel pass between the nozzles 8 on to the plate

4 from whence they are blown by jets of steam of relatively weaker pressure issuing from a second series of nozzles 9. The blast chamber member 7 shown in Figs. 3 and 4, is provided with a pair of chambers 11 and 12 in communication with the series of nozzles 8 and 9 respectively. Tubular extensions 13 and 14 are disposed at the rear of the blast chamber member and serve as inlet members co-operating with passages 15 and 16 for admitting steam under pressure to the chambers 11 and 12 respectively.

In order to overcome the action of the heat in the fire box upon the distributor plate I have provided means for projecting jets of steam at various angles in a plane disposed below and substantially parallel to the bottom of the distributor plate 4. This is accomplished by positioning inlet extension members trunnions 13 and 14 slightly above the bottom 5 of the fire door opening 6 and providing perforations 17 and 18 in each of said projections. The perforations 17 may be substantially at right angles to the axes of the inlet extensions while the perforations 18 are disposed at angles toward the center of the distributor plate 4 so that when jets of steam are forced through the perforations there will be provided practically a solid blanket of steam under pressure beneath the distributor plate. The blanket of steam is made complete and more effective because the diagonal jets of steam from perforations 18 strike and intermingle with one another and also with the streams or jets from the perforations 17. Thus it will be noted that the means for conducting the fuel to the distributor nozzles are at the same time utilized for projecting the blanket of steam beneath the distributor plate so that the distributor plate is practically insulated from the direct action of the heat in the fire box.

While I have disclosed a distributor plate substantially as shown in my United States Letters Patent No. 1,497,014, issued June 10, 1924, it will be readily apparent that practically the same means and operating upon the same principle, may be applied to other distributor mechanisms for example as shown in my United States Letters Patent #984,662,

issued February 21, 1911. In short, the essence of this invention lies in providing means for conducting steam or air under pressure to a plane below and immediately adjacent the exposed bottom of the distributor plate and projecting such steam or air in streams, disposed at various angles in said plane whereby an enveloping protective blanket is provided.

10 The faces surrounding the perforations 17 and 18 are respectively disposed at right angles to the axes of such perforations. For the angularly disposed perforations therefore, bosses or lugs 19 are provided with faces 15 20 in order that all jets of steam may be projected to equal advantage.

What I claim is:

1. In a device of the class described the combination with a fuel distributor plate, of 20 a blast chamber member, and inlet means for admitting steam to the blast chamber member, said inlet means having perforations disposed at varied angles in a given plane for directing intermingling jets of steam beneath 25 the distributor plate.

2. In a device of the class described the combination with a distributor plate having a face exposed to fire, of a blast chamber member having a pair of non communicating 30 chambers therein and passages terminating in said chambers, and tubular extensions carried by the blast chamber member for directing steam under pressure through the passages into the chambers in said member, the 35 tubular extensions having perforations in the walls thereof for emitting jets of steam at various angles across the exposed face of the distributor plate whereby to entirely displace heated air from the exposed face of the distributor plate when operatively mounted in a fire box.

3. In a fuel distributing mechanism the combination with a distributor plate having a face exposed to fire, of a blast chamber 45 member, tubular members disposed in alignment with the exposed face of the distributor plate, and lugs on the tubular members having flat faces disposed at various angles in planes perpendicular to the exposed face of 50 the distributor plate, the said lugs having perforations extending therethrough at right angles to the aforementioned faces and communicating with the interior of the tubular member whereby steam under pressure in the 55 tubular members will be projected in intersecting jets at various angles in a plane substantially parallel with the exposed face of the distributor plate.

4. The combination with a distributor having a plate normally exposed to fire, of means 60 comprising perforate tubes for projecting intermingling jets of steam in substantial parallelism with the exposed face of the plate whereby a fire protective blanket of steam is 65 maintained upon said exposed face of the

plate for displacing heated air immediately beneath the plate.

5. In a device for protecting articles having surfaces normally exposed to fire, the combination of tubes for carrying steam under pressure mounted adjacent the exposed surfaces, and lugs carried by the tubes and having faces disposed at various angles to one another and in planes substantially perpendicular to the exposed surface, the lugs and tubes having a plurality of perforations therein disposed in a plane substantially parallel to the exposed surface, each perforation extending at substantially right angles to the face of its respective lug.

6. In a fuel distributing mechanism, the combination with a distributor plate having a lower face exposed to fire, of a blast chamber member having a pair of non-communicating chambers therein, said member having 85 perforations therein for directing blasts of steam from the chambers over the top of the distributor plate for moving fuel over said plate, tubular members disposed in a plane below the lower exposed face of the distributor plate and communicating one each with the noncommunicating chambers, lugs on 90 said tubular members having flat faces disposed at various angles in planes perpendicular to the lower exposed face of the distributor plate, said lugs having perforations extending therethrough at right angles to the aforementioned faces and communicating with the interior of the tubular members for 95 directing steam under pressure through said perforations whereby the jets of steam are adapted to be deflected one by another adjacent the outer exposed edge of the distributor plate.

7. In a fuel distributing device the combination with a fire box of a fuel distributing plate extending into the fire box and having its bottom face exposed to fire in the fire box, a blast chamber member having suitable perforations therein to direct the blasts for effecting movement and distribution of fuel over the distributor plate and into the fire box, and means for supplying steam under pressure to the blast chamber member, said means being disposed in a plane immediately beneath the bottom face of the distributor plate and provided with perforations from which jets of steam are projected at various angles in a plane below and substantially parallel to the bottom face of the distributor plate and serving to effect displacement of fire and heated air immediately beneath the distributor plate for protecting said plate.

8. In a fuel distributing mechanism the combination with a fire box and a fuel distributor plate projecting into the fire box above a bed of fuel, of means for directing constant jets of steam under pressure at various angles in a plane beneath and parallel to the bottom face of the distributor plate

for displacing heated air from the bottom face of the plate.

9. In a fuel distributing mechanism, the combination with a fire box and a fuel distributor plate projecting into the fire box above the bed of fuel, of means for directing intermingling jets of steam under pressure in a plane beneath and substantially parallel to the bottom face of the distributor plate for 10 blanketing the same from the heat from the bed of fuel.

10. In a fuel distributing mechanism, the combination with a fire box and a fuel distributing member in said fire box having a 15 surface normally exposed to the fire, of means for protecting said surface comprising tubes carrying steam under pressure mounted adjacent the exposed surface, and lugs carried by said tubes and having faces disposed in 20 planes substantially perpendicular to the exposed surface, the lugs and tubes having a plurality of perforations therein directed to project intermingling jets of blanketing steam in a plane substantially parallel to the 25 exposed surface and between said surface and the fire.

In testimony whereof, I have hereunto subscribed my name this 17th day of July, 1924.

WILLIAM T. HANNA.
